ABSTRACT: A dual mode fuze explosive train which comprises the combination of a superquick firing pin assembly and an inertial firing pin assembly whereby the inertial pin comes forward to initiate the stab primer when the fuze hits a soft target and the superquick firing pin is driven into a stab detonator thereby initiating the end initiator when a hard target is struck.

DUAL MODE FUZE EXPLOSIVE TRAIN

BACKGROUND OF THE INVENTION

The present invention relates to a dual mode fuze explosive train.

To meet the needs of the overall performance of guided missiles, much time has been expended on exploration of new fuze design, improved fuze design, improved fuze systems for specific applications, and technical evaluation of fuze systems. The present invention provides a dual mode fuze explosive train which improves the performance of the antipersonnel/antimaterial cluster weapons. The general purpose is to provide a fuzing system which is simple, inexpensive and reliable. The invention provides such a system which will initiate detonation of a warhead if either a hard target is hit or a soft target is hit.

DESCRIPTION OF THE DRAWING

FIG. 1 is an enlarged view in section of a portion of a 20
bomblet incorporating the present invention;

FIG. 2 is an end view of the fuze housing; and

FIG. 3 shows the end cap which covers the fuze section of
the bomblet.

DESCRIPTION OF THE PREFERRED EMBODIMENT

Referring now to the drawing there is shown in FIG. 1 a
bomblet in partial section which incorporates the present in-
vention. The bomblet comprises a casing 11 which is formed
of notched steel wire high explosive 14 such as HMX, or RDX.
A dual fuze explosive train assembly designated generally as
numeral 15 is secured by suitable means to the nose end of
said bomblet casing 11 and is adapted to initiate the booster
16 which is positioned at the apex of cone liner 13. Booster 16
is connected to the fuze train assembly 15 by a detonating
transfer train 17 and end initiator 34. The dual fuze explosive
train assembly 15 comprises a fuze housing 18 provided with a
cavity into which is positioned a cylindrically shaped rotor 19
mounted for rotation about its longitudinal axis. A gear train
mechanism 20 is mounted to the side of fuze housing 18 and is
suitably attached to rotor 19 for driving said rotor. Rotor 19
has two vertical bores near each end one which contains a stab
detonator as shown at 21 and the other a stab primer 22 as
shown. Also rotor 19 is provided with a transverse bore con-
taining a delay composition 23 as shown between the two ver-
tical bores. Rotor 19 is positioned in the fuze housing 18 so
that the end containing stab detonator 21 is adjacent a firing
pin retainer 24 which is fixed in fuze housing 18. The end con-
taining stab primer 22 is adjacent an inertia firing pin assembly
25 which is also fixed in said fuze housing as shown. Rotor 19
is positioned so as to be out of line or in a safe position and is
driven to the armed position shown. The primer 22 and
detonator 21 which when actuated conduct the detonation
wave through the end initiator 34 and detonating transfer train
17 to the booster 16 which in turn detonates shaped charge
12.

The nose end 26 of fuze housing 11 shown in FIG. 2 is pro-
vided with a lever plate 27 positioned adjacent firing pin
retainer 24, which moves to actuate said pin when a hard tar-

get is struck.

Fuze housing 18 is provided with a nose probe 28 as shown
in FIG. 3 which slides firmly over the outside of fuze housing
18 and is a part of bomblet casing 11. As shown nose probe 28
5 is provided with a hollow cone-shaped end having a slidably
mounted striker 29 positioned therein which is secured by a
pair of restraining pins 30.

Inertia firing pin assembly 25 comprises a delay firing iner-
tia weight 32, and a firing pin 33 which will drive into the stab
10 primer 22 when a soft target is hit. Stab primer 22 initiates a
propellant charge 35 and the pyrotechnic time delay composi-
tion 23 which burns to the sensitive end of and initiates the
stab detonator 21. Ultimately the stab detonator fires and
15 transmits a detonation wave via the end initiator 34 and
transfer train 17 to the booster 16 and thence to the shaped
charge explosive resulting in an airburst of the warhead.

When the bomblet impacts a hard target such as armor,
metal clad body, rock or the like, the striker 29 on nose probe
28 defeats two restraining shear pins 30 and pushes against
lever plate 27 positioned on fuze housing 18 which actuates
superquick firing pin 31 held in retainer 24. Firing pin 31 now
20 stabs detonator 21 which causes it to explode sending a
detonation signal via the end initiator 34 and transfer train 17
to the booster 16 which transmits the wave to the main charge
25 12. The target will then be subjected to shaped charge war-
head action.

What is claimed is:

1. A dual mode hard and soft target fuze explosive assembly comprising:
30 a fuze housing defining a cavity;
a lever plate positioned at the end of said housing;
a rotor mounted for rotation about its longitudinal axis
within said cavity; said rotor being provided with two in-
ternal vertical recesses near each end and a centrally
positioned transverse recess;
a gear means positioned outside said housing secured to said
rotor and adapted to drive said rotor;
explosive means filling said recesses in said rotor comprising
a stab primer composition in the vertical recess on the
end adjacent said gear means; a stab detonator composi-
tion in the recess at the other end of said rotor and a
pyrotechnic delay composition filling said transverse
recess between the two vertical recesses;
a fixed firing pin retainer positioned in said housing ad-
jacent said stab detonator and a firing pin means slidably
mounted in said retainer and held in a nonfiring position;
means outside said housing which moves said lever plate
against said firing pin means urging said pin from said
retainer to a firing position when a hard target is hit;
an inertial firing pin assembly in a fixed position in said
housing adjacent said stab primer composition; said as-
sembly comprising an inertia weight and a firing pin ad-
jacent thereto whereby when a soft target is struck said
weight drives said pin into the stab primer which initiates
said pyrotechnic time delay causing initiation of the sensi-
tive end of said stab detonator and subsequent firing of
said detonator which transmits detonation waves
therefrom.
